C. M. MacCAMEY.

GAS BURNER.

APPLICATION FILED SEPT. 29, 1919.

1,359,405.

Patented Nov. 16, 1920.

INVENTOR

Charles M. MacCamey

Edmund A. Stacey:

ATTORNEY

UNITED STATES PATENT OFFICE.

CHARLES M. MACCAMEY, OF HUNTINGTON PARK, CALIFORNIA.

GAS-BURNER.

1,359,405.

Specification of Letters Patent. Patented Nov. 16, 1920.

Application filed September 29, 1919. Serial No. 327,047.

To all whom it may concern:

Be it known that I, CHARLES M. MACCAMEY, a citizen of the United States, residing at Huntington Park, in the county of 5 Los Angeles and State of California, have invented new and useful Improvements in Gas-Burners, of which the following is a specification.

This invention relates to gas burners, and 10 is particularly adapted to be projected into the fire box of a furnace for the burning of natural gas under a boiler, or in other situations where a uniform heat is required.

The object of my invention is to provide a 15 gas burner construction which will be simple, durable and efficient, and which may be quickly adjusted to a furnace of any design or pattern.

Another object of my invention is to provide 20 a gas burner construction whereby the flow of gas through said burner may be readily controlled and regulated to a nicety, and to provide means whereby air may be mixed with the gas in the exact required proportions, in order to provide a perfect 25 combustion, thereby eliminating all offensive odors, as well as consuming the effective gas units.

Other objects will be disclosed in the following 30 description, will be pointed out in the claims, and embodied in the accompanying drawings, in which:

Figure 1 is a vertical longitudinal section, through my burner construction, showing it 35 applied to the front wall of a furnace as it would appear when in use.

Fig. 2 is a transverse section of my invention taken on the line 2—2 of Fig. 1, viewed in the direction indicated by the arrows.

In carrying out my invention I employ an 40 annular head 10 adapted to be secured to the front wall of the fire box door 11 of a furnace 12, by means of cap screws 13. The door 11 is provided with an annular aperture 45 14, adapted to be covered by head 10, which is provided with an aperture 15, into which is threaded the pipe 16, which projects through aperture 14, and extends a suitable distance into the fire box of the furnace, and 50 serves as a mixing chamber for the gas and air.

An annular ring 17, the bore of which is of approximately the same diameter as aperture 15 and adapted to register therewith, is 55 secured to the head 10 by means of the cap screws 13, and interposed between the oppo-

sitely disposed surfaces of head 10 and ring 17 are the spacing plates 18 and 19 which are also secured in place by means of the cap screws 13. A rectangular slot is formed between the edges 20 and 21 of plates 18 and 19, and the oppositely disposed surfaces of head 10 and ring 17, in which are slidingly mounted damper plates 23 and 24, provided respectively with the handles 25 and 26. The 60 damper plates 23 and 24 are for the purpose of regulating the quantity of air passing into the mixing chamber 16, and are adapted to meet at the diametrical center of the bore of ring 17, to cut off the flow of air to said 65 mixing chamber, or to be moved outwardly and away from each other so as to admit the desired quantity of air to said mixing chamber. The oppositely disposed vertical edges of the damper plates are each provided with a semi-circular notch 27 and 28, so as to permit of a complete closure of the entrance to the mixing chamber 16 when desired, the diameter of the two notches being approximately the same as the diameter 70 of the reduced end of the burner nozzle.

Projecting outwardly from the ring 17, and preferably formed integral therewith are arms 32 and 33, which support on their outer ends an annular plate 35, which is provided with a centrally disposed threaded bore 36 in which a burner nozzle construction is secured. The burner nozzle preferably consists of a stationary and a movable member, the stationary member 38 consists 85 of a gas discharge pipe of cylindrical form provided with a threaded end 37, which engages the threaded bore 36 in the plate 35, the outer end 39 of said pipe being closed, and its exterior annular edge is beveled as at 90 40. The outer end of the gas discharge pipe is provided with a plurality of radially disposed gas outlet openings 41, and is exteriorly threaded as at 42 for the reception of the interiorly threaded end of the movable 95 member 44 of the burner nozzle, which member is adapted for reciprocatory movement thereon. Preferably the bore of the movable burner nozzle member is of a larger diameter at its central portion than the exterior diameter of the stationary member, thus forming 100 between the two members an annular gas passage or chamber 46. The outer end of passageway 46 is annularly beveled so as to form a seat 47 against which the beveled end 105 of tube 38 contacts, so that when the outer burner nozzle member is reciprocated on the 110

stationary member the flow of gas through the annular passageway or chamber 46 to the bore or outlet 48 of the burner nozzle 30 may be easily and readily regulated.

- 5 Secured to plate 35 by means of cap screws 49, is the plate 50 provided with the centrally disposed threaded bore 51 adapted to receive the gas supply pipe 52 which communicates with pipe 38, and in order to prevent leakage between these two members, a gasket 53 is interposed between plates 35 and 50.

10 The operation of my apparatus is as follows: Gas is admitted into the pipe 52 from a suitable source of supply (not shown) and passes into pipe 38; thence through slots 41 into the annular passage 46. The movable member 44 is then turned in the proper direction to adjust the angular passage formed 15 between the seat 47 and the beveled end 40 of tube 38, to admit the desired amount of gas into the nozzle 48 and thence into the mixing chamber 16. The handles 25 and 26 are then grasped by the attendant and the dampers 27 and 28 are manipulated to admit 20 the necessary amount of air into the mixing chamber 16.

25 By the above recited construction it will be seen that the proper and desired quantities of gas and air may be admitted into the mixing chamber to form a perfect combustion, and that the flow of gas into the mixing chamber may be completely shut off at a point close to the outlet nozzle, thereby reducing 30 to a minimum the quantity of unconsumed gas which would be admitted into the mixing chamber, thus avoiding any odor.

35 What I claim is:

1. A gas burner, comprising a pipe adapt-

ed to communicate with a source of gas 40 supply, and having a closed tapered end and provided with a plurality of radial perforations adjacent said end, and a sleeve mounted on said pipe adapted for rotatable and longitudinal movement on said pipe, provided with a tapered seat adapted to engage 45 with said tapered end, and to open and close communication between said pipe and a burner nozzle.

2. A gas burner, comprising a head adapted 50 to be secured to the front wall of a furnace, an inwardly projecting open ended pipe supported on said head, a pair of damper plates mounted in guideways in said head, and adapted to project across said pipe, a gas supply pipe supported on arms extending 55 outwardly from said plate, and adapted to project into said first mentioned pipe, and a valve arranged in said gas supply pipe arranged adjacent its inwardly projecting 60 end.

3. In combination with a furnace, of an open ended tube arranged in the front wall of said furnace and projecting thereinto, a gas supply pipe leading to said furnace, the 65 end of said supply pipe terminating adjacent the outer end of said tube, a burner nozzle adjustably secured to the free end of said gas supply pipe, the end of said nozzle projecting into said tube, and a pair of damper 70 plates slidably arranged in front of said tube adapted to control the volume of air delivered to said tube.

In witness that I claim the foregoing I have hereunto subscribed my name this 15th 75 day of September, 1919.

CHAS. M. MacCAMEY.
